DESIGN FOR A DRESS

Abraham Samuels, New York, N. Y.

Application September 9, 1938, Serial No. 79,801

Term of patent 3½ years

To whom it may concern:

Be it known that I, Abraham Samuels, a citizen of the United States, residing at New York, in the county and State of New York, have invented a new, original, and ornamental Design for a Dress, of which the following is a specification, reference being had to the accompanying drawing, forming part thereof, wherein—

Figure 1 is a front view, and
Fig. 2 is a back view of a dress showing my new design.

I claim:
The ornamental design for a dress, substantially as shown.

ABRAHAM SAMUELS.
